(57) **CLAIM**

The ornamental design for a smart hub, as shown and
described.

DESCRIPTION

FIG. 1 is a perspective view of a smart hub, showing our new
design;

FIG. 2 is a top view of the smart hub of FIG. 1;

FIG. 3 is a bottom view of the smart hub of FIG. 1;

FIG. 4 is a front view of the smart hub of FIG. 1;

FIG. 5 is a back view of the smart hub of FIG. 1;

FIG. 6 is a left side view of a smart hub of FIG. 1; and,

FIG. 7 is a right side view of a smart hub of FIG. 1.

The broken lines in the drawings show portions of the smart
hub and form no part of the claimed design.
